Albert Ediertenich,
ATTORNEY.

UNITED STATES PATENT OFFICE

2,442,796

THREAD TENSIONING MEANS

George Ostrom Young, Robesonia, Pa., assignor
to Vanity Fair Mills, Inc., Reading Pa., a corporation of Pennsylvania

Application October 10, 1946, Serial No. 702,511

4 Claims. (Cl. 66—86)

1

My invention relates to knitting machines and it has for its object to provide a novel, simple, resilient thread tensioning device over which the thread from the beam passes to the thread guides.

A further object is to provide a means for mounting the guide so that it may be adjusted to increase or decrease the tension on the thread as may be found desirable.

To the attainment of the aforesaid object, the invention resides in the novel construction, combination and arrangement of parts which will first be fully described and then be specifically pointed out in the appended claims, reference being had to the accompanying drawing in which:

Fig. 1 is a cross section of a portion of a knitting machine embodying my invention.

Fig. 2 is a perspective view of one end of the device.

Fig. 3 is a side elevation of the invention, looking in the direction of the arrow in Fig. 2.

Fig. 4 is an elevation and part section of another embodiment of the invention.

Fig. 5 is a cross section on the line 5—5 of Fig. 4 looking in the direction of the arrows.

Fig. 6 is a section on the line 5—5 of Fig. 4 looking in the direction opposite to Fig. 5.

In the drawing in which like numerals and letters of reference indicate like parts in all the figures, the reference numerals used to indicate the several parts of the machine are the same as those used to designate the same parts shown in the drawings of my application for patent on a knitting machine, filed October 15, 1945, Serial Number 622,321, of which application the present application is a continuation in part.

In the drawing 16 designates one of the cross frames of the machine; 81 designates a beam shaft, 80 a beam and T¹ the thread. The thread from the beam passes around a roller 93 on a shaft 94 and from the roller the thread passes over a bar 121. The bar is fixed. From the bar the thread passes over the curved edge 75 of a thin resilient plate 75^x. The plate 75^x along its edge opposite the curved edge is securely mounted on a fixed rod 73. Passing over the curved edge 75 the thread goes to the thread guide 124.

The thread guide 124 is mounted on a thread guide bar 121^x which is attached to the thread-guide-bar-carrying arm 70. The arm 70 is movable along a collar 68 of a fixed shaft 66 but is prevented from turning on the collar by means of grooves and splines 69.

147 designates a hollow shaft which connects the end and intermediate frames 16 together. The roller 93 hereinbefore referred to has its

shaft 94 journaled in the short arm of a bell crank lever 89, the long arm of which has a roller 115 that is held to engage a cam 113 by means of a spring 111. The cam 113 is mounted on a suitably driven rotatable shaft 55. The shaft 55 has an eccentric 56 for the strap 58 whose arm 57 is pivoted at 59 to a rod 51 that reciprocates in a bearing bore in a fixed shaft 50. The rod 51 has a head 52 that carries a sinker-nib bar 53 on which a sinker nib 54 is mounted to cooperate with the fixedly mounted sinker 48 that is attached to a fixed sinker bar 48. 20 is a vertically reciprocal shaft or rod which has a head 21 on which a needle bar 22 is fixedly secured and in which a rod 27 is reciprocally mounted. The rod 27 carries a tongue bar 26 on which the needle-hook-closing tongue 33 is mounted. The needle 24 is mounted on the needle bar 22. The rod 27 is spring-pressed against 20 a fixed cam 32 which is mounted on a bar 31 and operates the hook closing tongue as the rod 20 works up and down to open and close respectively the needle hook.

From the thread guide 124 the thread passes 25 to the needle while the knit fabric passes over a roller 118 to a winding up roller (not shown).

The rotation of the shaft 55 and the reciprocations of the rod 20 are timed to effect knitting operations during which the thread T¹ is let off 30 the beam by the action of the cam 113 on the roller 115, the resilient plate 75^x taking the place of the usual spring-loaded tension rods heretofore employed in tricot machines to take care of slight variations in the thread tensions.

35 By using a single plate 75^x the use of a spring tensioned rod is avoided and a more uniform action is provided for than can be had by a pivoted tension bar such as heretofore used.

In the embodiment shown in Figs. 4 to 6 inclusive, the rod 73^a which carries the resilient plate 75^a has an end 73^b mounted eccentrically in a socket 73^c or a rotatable body 73^d whose threaded stud 73^e passes through a bearing hole in the frame 16^a and carries a clamp nut 73^f and a 45 squared wrench-receiving portion 73^g. The end 73^b is held from turning in the socket 73^c by a key 73^f and set screw 73^g.

The plate 75^a in this embodiment is curved about the shaft 73^a and has one edge fastened 50 to the shaft by screws 75^b. The thread passes over the plate 75^a as indicated by the broken line T¹ in Fig. 6, and the arrangement is such that as the stud 73^e is turned the rod 73^a will be swung about the axis of the lug 73^f and the amount of 55 tension on the thread itself will be increased.

or decreased depending upon the point of contact with the thread on the curved plate. Due to the eccentric arrangement, the angle from the end of the tension plate to the hole in the thread guide (not shown) will remain approximately the same, which is very important in some cases. The rod 73 with plate 75^x may be mounted in the body 73^d in lieu of the rod 73^a if desired.

In this application I make no claim to the mechanism shown in Fig. 1 other than the elements 73, 75, 75^x as such constitute in general the subject matter of my original application, Serial Number 622,321, aforesaid.

From the foregoing description taken in connection with the accompanying drawing it is believed my invention and its advantages will be readily understood by those skilled in the art.

What I claim is:

1. In a knitting machine having a beam and thread guides, the improvement which comprises a resilient thread-tensioning plate rigidly mounted at one longitudinal side and free at the other end over which the thread from the beam passes to the thread guides, said plate extending over the full operating width of the machine, said resilient tension plate being mounted on a rod which in turn is carried by a body journaled eccentrically with respect to said rod and having means to hold said rod and plate in any desired adjusted position.

2. In a knitting machine having a beam, thread

guide and thread let-off mechanism, the improvement which comprises a fixed rod, a resilient thread-tensioning plate mounted along one of its longitudinal edges on said rod and having its other longitudinal edge curved around said rod and spaced from the same, the thread from the beam let-off mechanism passing over said other longitudinal edge to the thread guide.

3. In a knitting machine having a beam and a thread guide, the improvement which includes a body having a rotatably adjustably mounted stud and an eccentric socket, a rod secured in said socket and a thread tensioning plate secured adjacent one longitudinal edge to said rod.

4. In a knitting machine having a beam and a thread guide, the improvement which includes a body having a rotatably adjustably mounted stud and an eccentric socket, a rod secured in said socket and a thread tensioning plate secured adjacent one longitudinal edge to said rod and curved about and spaced from said rod save where it is secured to the rod.

GEORGE OSTROM YOUNG.
